UNITED STATES PATENT OFFICE

JOHN HINES, OF ASTORIA, NEW YORK, ASSIGNOR TO SEGAL LOCK & HARDWARE CO., INC., OF NEW YORK, N. Y., A CORPORATION OF NEW YORK

LOCK

Application filed February 1, 1928. Serial No. 250,982.

This invention relates to a functionally and structurally improved lock.

It is an object to provide a device of this character which may, without modification of its parts, be capable of application to various types of closures;—and more specifically stated by means of this invention a lock is furnished embodying a construction by means of which it will be unnecessary to modify the parts thereof regardless of the width or thickness of the closure irrespective of the direction of swing thereof.

It is a further object of the invention to construct an improved lock which preferably will embody an arrangement of parts making it virtually "jimmy-proof".

Still another object is that of constructing a lock in which the cylinder may at all times be operated and in which a minimum of effort will be required for such operation.

An additional object is that of providing a lock embodying a relatively simple construction involving comparatively few parts, individually of a rugged type, and which parts may be assembled readily to furnish a lock operating over long periods of time, with freedom from mechanical difficulty.

Other objects of the invention will be apparent upon referring to the following specification and the annexed drawings, which latter illustrate one practical embodiment of the invention and in which:

Fig. 1 is a front elevation of a lock embodying the improved construction of the present invention;

Fig. 2 is a rear view thereof with the backing plate broken away to disclose the underlying construction;

Fig. 3 is an enlarged transverse sectional view taken through the lock and showing the same applied to a closure;

Fig. 4 is a perspective view of a portion of the outer end of the lock-casing and the bolt-keeper and strike;

Fig. 5 is a similar view of one form of operating connection which may be utilized; Fig. 6 is an enlarged fragmentary sectional view taken along the lines 6—6 of Fig. 2, and Fig. 7 is a plan view of the knob nut.

In these views the numeral 10 indicates

a lock-casing which may be of any desired configuration, material and exterior finish, and which in the embodiment illustrated mounts a knob 11 centrally disposed upon its inner face. The casing 10 has an extended portion 12 and a keeper 13 is provided which, as shown, is disposed adjacent thereto. Mounted for movement with respect to the lock-casing—in a manner hereinafter brought out—is a bolt 14 which is projectable through an opening in the outer end of the casing portion 12 and which is preferably provided with a latch surface 15. This bolt, if the lock is applied to a swinging closure, cooperates with a strike surface 16 forming a part of the keeper 13, and at this time it will be observed that the latter is provided with projecting portions 17 and 18 which enter recesses 19 formed in the forward portion of the lock case. Thus, as the closure to which the lock is applied, is swung towards seated position, the latch surface 15 will cooperate with the strike surface 16 to retract the bolt and the latter will subsequently—as hereinafter described—be automatically projected to extend within the body of the keeper and prevent an accidental or unauthorized opening of the closure by a swinging movement, it being apparent that the flange and recess portions 17, 18 and 19 will inter-engage to prevent a forcible separation thereof.

The rear face of the lock casing is closed preferably by means of a cover-plate generally indicated at 20 and this casing together with the keeper may be secured to a closure in any desired manner as, for example, by passing screws through openings 21 formed in their bodies, the ends of these screws having firm bearing in the body of the door or other closure to which the lock is applied.

In the exemplified embodiment of the invention, the bolt 15 is mounted upon the outer end of, or forms an integral part of 95 a shank 22. This shank is encircled by a spring 23, the rear end of which has slideable bearing with a forked lug 24 extending from the lock case, it being noted, if desired, that a washer 25 may be interposed between 100

this lug and the rear end of the spring. The forward end of the latter bears against the bolt head so as normally to urge the same outwardly to the position shown in Fig. 2, the lug serving as a guide for the shank during the sliding movements of the latter.

In order to effect a retraction of the bolt by actuating the handle or knob 11, the shaft of the latter may carry at its inner end a lever 26 which will obviously rock as the knob is oscillated. Mounted for movement within the casing is a traveler block 27, the edges of which slidably bear against spaced track portions 28 preferably forming integral parts of the casing and serving to guide the traveler. This member is normally maintained in the position shown in Fig. 2 by means of a spring 29, one end of which bears against the flange of the casing, the opposite end thereof bearing against the rear edge of the block, and if desired, encircling a projection 30 forming a part thereof. Adjacent its rear edge, this block is also formed with flange portions 31 and 32, the first extending downwardly and adjacent the rear edges of the lever 26, the latter extending upwardly, and the purpose thereof being hereinafter brought out. Thus, obviously, as the knob 11 is oscillated, the lever 26 will be rocked to bear against one of the flange portions 31 and retract the traveler block. Such retraction will cause a corresponding movement on the part of the bolt 14, due to the fact that the forward edge of the block is formed with a forked portion 33 partially encircling the rear of the shank 22, which to this end is extended beyond the lug 24, and further for the reason that it bears against a head 34 formed at the rear end of the shank. Thus a partial rotation of the knob will cause the traveler to move rearwardly along its tracks 28 carrying with it the shank 22 and the bolt affixed thereto, it being obvious that during such movement both the springs 23 and 29 will be compressed.

Positioned within the body of the lock casing, and adjacent both ends thereof are bolt retracting mechanisms, each including a rotatable sleeve 35 which has bearing within the casing and in turn serves as a bearing for a second sleeve 36 which is disposed in axial alignment with respect thereto, this second sleeve in turn having rotatable bearing in the cover plate 20. The bores 37 of these sleeves are preferably irregular in cross-section, and, as shown are square. Secured to the sleeve 35 is a cam-plate 38, one portion of which is extended to bear against the forward edge of the flange 32, another edge thereof being formed with a recess 39 for the reception of a locking dog 40. The latter is slidably mounted between suitably disposed lug portions 41 forming a part of the casing and extending from the inner face thereof. The

sleeve 36 carries a crank portion 42 which extends to a point immediately in advance of the head 34 of the shank. Conceding that the dog 40 is not in engagement with the recess of the plate 38, it will be obvious that both the sleeves 35 and 36 may be turned, this resulting in a retraction of the traveler block and bolt 14 and a consequent compression of the springs 22 and 29. If, on the other hand, the sleeve 35 is not moved but the sleeve 36 is turned, it will be apparent that by means of the crank 42 the bolt will be retracted against the action of only spring 22, the traveler and its associated parts under these conditions remaining stationary.

The foregoing mechanism identified generally by the numerals 35 to 42 inclusive is, as aforesaid, duplicated adjacent each end of the lock casing, these mechanisms being preferably as shown positioned equi-distant from the center of the casing or the shank 22.

The forward portion of the lock casing rockingly mounts a lever 43 which has the dogs 40 secured one to each of its arms, this lever being operated, as for example, by pins 44 likewise associated with the outer ends of its arms and extending as in Fig. 4 to be accessible from the exterior of the casing. These pins are preferably integral with the dogs 40, and spring pressed detent members 45 are mounted one by each of these elements and engage with irregular portions 46 formed to the outer lugs 41. Accordingly the position of the lever 43 and the dogs will be maintained to optionally engage or clear the plates 38 adjacent which they are positioned.

As shown in Fig. 3, the lock casing is applied to a closure 47 and suitably secured thereto, as for example, by screws 48. This closure is bored as at 49 and 50 and the first bore receives a cylinder 51 suitably retained against movement with respect thereto, as for example, by a facing plate 52. The plug of this cylinder is operated by a key (not shown) in order to turn a tail piece 53. This tail piece extends within a slot formed in the base of a thimble 54, the latter being mounted rotatably upon a plate 55 and having its inner end terminating in a portion 56, corresponding in contour to the bore of the sleeves 35 and 36 projecting into the latter.

The facing plate 52 rotatably mounts a knob 57 which as shown is preferably in permanent association therewith and this knob receives and moves a spindle 58 which extends within and engages the bores of both sleeves 35 and 36. A set screw 59 is associated with the knob 57 and the latter has a recess 60 of a length adequate to receive the outer end of the spindle 58, it being here noted that this end of the spindle is preferably split as at 61, in order that it may bear resiliently against the inner end of the set screw to prevent the same from loosening accidentally.

In using this lock the closure is as afore-

stated bored as at 49 and 50, after which the facing plate is positioned and the cylinder 51 is secured against movement. The plate 55 together with the thimble carried thereby will now be arranged to overlie the sleeves 35 and 36 which are uppermost and regardless of whether the closure be a left or a right-hand one, the lock casing is thereupon positioned to have the bolt extend beyond the outer edge of such closure.

Thereupon, it will be obvious that the tail piece of the cylinder-plug will extend through the slot of the thimble so that when the plug is turned the crank arm 42 will be rocked to 10 retract the shank 22 and the bolt associated therewith, thus permitting an opening of the closure. In this connection, it will be observed that only the spring 23 will be compressed, the sleeve 35 remaining stationary. 20 This is of particular value in that obviously but little effort will be required to operate the lock by means of a plug, and there will be no danger of the latter distorting or shearing.

It will, furthermore, be observed incident 25 to the construction employed that the knob 57 is at all times associated with the facing-plate. Consequently, these parts will always occupy proper relative positions and it will be unnecessary for a locksmith to attach them 30 with consequent danger of their becoming subsequently and accidentally detached. The only consideration which is necessary in applying the lock is that of associating the thimble or similar actuating member with those 35 sleeves 35—36 which are uppermost, and in line with the tail piece of the cylinder. Aside from this, the lock without modification of its construction may be applied to closures swinging in either direction to efficiently retain them in seated position. Also (within the usual limits) the lock, and particularly the spindle 58 thereof, may be applied to closures of different thicknesses without it being necessary to cut this spindle. Obviously, 40 while the knob 11 will at all times retract the locking bolt from within the keeper, the knob 57 may be prevented from actuating the parts in this manner by simply projecting the proper (i. e. lowermost) dog to achieve this result. In any event, the lock will at all 45 times be free to be key-actuated.

Finally, in connection with the mounting of the knobs, it will be observed that as on the righthand side of Fig. 3 the knob may have a 50 groove within which the inwardly extending annular flange of a collar 62 projects, this collar being associated suitably with the lock casing. Preferably, the retention of the knob is effected as shown in connection with the 55 knob 57. It will be observed that this knob has a reduced end portion 63, the exterior of which is screw-threaded and mounts a nut 64. This nut bears against a shoulder 65 formed in a collar 66, extending from the plate 52 and, as a consequence, it will be

appreciated that while the knob may be tightened to a point at which all axial play will be prevented still it may be turned freely. To prevent relative movement of the knob and nut, the latter has an inwardly extending flange portion 67 which presents a star shaped edge, portions of which may be engaged by the spindle when the latter is in position. Thus, due to the fact that the spindle is prevented from turning with respect to the knob and bears against the nut, it will be obvious that the latter will turn with the spindle, thus preventing any play from coming into being.

It is obvious that numerous changes in construction and rearrangement of the parts might be resorted to without the slightest departing from the spirit of the invention as defined by the claims.

Having described my invention, what I claim as new and desire to secure by Letters Patent is:

1. A lock including, in combination, a casing, a knob, a spindle connected to said knob, lock mechanism to be actuated by said spindle, means for rotatably retaining the knob against other than rotational movement with respect to said casing and including a nut, and means forming part of the nut and engaged by the spindle to prevent movement of the former with respect to the knob.

2. A lock including, in combination, a casing to be applied adjacent either edge of a closure and to extend toward said edge, a bolt movable with respect to such casing, means for projecting and retracting said bolt and disposed within said casing, a key operated mechanism to occupy a predetermined position with respect to a closure to which said lock is to be applied and means whereby such mechanism may be connected to said means irrespective of the direction in which the casing extends and without disturbance of the relationship of the key mechanism with respect to the closure.

3. A lock including, in combination, a key operated mechanism and a knob occupying predetermined relative positions with respect to a closure adjacent one of the edges thereof and to extend towards said edge, a casing to be applied to such closure, a bolt within said casing, means for projecting and retracting such bolt and means connecting said last named means with said knob and key operated mechanism and permitting of the lock casing being applied to extend in either direction with respect to the closure and without disturbance of the relationship of the knob and key mechanism with respect thereto.

4. A lock including, in combination, a key operated mechanism and a knob occupying predetermined relative positions with respect to a closure, a casing to be applied to such closure, a bolt within said casing, means

for projecting and retracting such bolt, means connecting said last named means with said knob and key mechanism and permitting of the lock casing being applied to extend in either direction with respect to the closure and without disturbance of the relationship of the knob and key mechanism with respect thereto and means extending from the casing to operate said bolt independently of such key mechanism and knob.

5. A lock including, in combination, a key operated mechanism and a knob occupying predetermined relative positions with respect to a closure, a casing to be applied to such closure, a bolt within said casing, means for projecting and retracting such bolt, means connecting said last named means with said knob and key mechanism and permitting of the lock casing being applied to extend in either direction with respect to the closure and without disturbance of the relationship of the knob and key mechanism with respect thereto and means substantially centrally disposed with respect to said casing and extending in a direction opposite from that in which the key mechanism and knob extends to operate said bolt independently of such mechanism and knob.

10. A lock including, in combination, a casing, a bolt movable with respect thereto, means for projecting and retracting said bolt and including a pair of springs, a key operated mechanism and a knob connected to said means to operate said bolt and means whereby one of such springs will be compressed when one of said last named means is actuated to operate the bolt and both springs will be compressed when the other of said last named means is actuated.

15. A lock including, in combination, a casing, a bolt movable with respect thereto, means for projecting and retracting said bolt and including a pair of springs, a key operated mechanism and a knob connected to said means to operate said bolt, and means whereby one of such springs is compressed when the key mechanism operates said bolt and both springs are compressed upon the knob being actuated.

20. A lock including, in combination, a casing, a bolt movable with respect to said casing, means within the latter for projecting and retracting said bolt and including two groups of similar mechanism, a key-operated element, a knob and means whereby said element or knob may be optionally connected to either of said mechanisms.

25. A lock including, in combination, a casing, a bolt, means within the casing for projecting and retracting the bolt and including two groups of elements, the individual units of each being relatively movable, means connected to each of such units whereby either of the same may effect an operation of said bolt, a key operated mechanism, a knob,

means connecting one of the units of one group to be operated by said key mechanism and means for connecting all of the units of another group to be operated by said knob.

30. A lock including, in combination, a face plate, a key operated mechanism and a knob associated with said face plate, the latter being adjacent one edge of a closure, a casing, a bolt projectable from one edge of such casing, means for operating the bolt and means for connecting said last named means reversibly to the knob and key mechanism without disturbing the relationship of the latter.

35. A lock including, in combination, a casing, a bolt removable with respect thereto, means for operating said bolt and including a sleeve, a key operated mechanism, a tail-piece extending therefrom and a thimble connected with said tail-piece and engaging the sleeve to effect an actuation of such bolt said thimble and sleeve being formed with irregular cooperating surfaces whereby rotational movement of one with respect to the other is prevented.

40. A lock including, in combination, a casing, a bolt movable with respect thereto, means for operating said bolt and including a sleeve, a key operated mechanism, a tail-piece extending therefrom and a thimble carried by the lock casing and extending into the bore of such sleeve and connected with said tail-piece to effect an actuation of such bolt said thimble and sleeve being formed with irregular cooperating surfaces whereby rotational movement of one with respect to the other is prevented.

45. A lock including a casing, a bolt, means for projecting said bolt beyond said casing, and two pairs of operating members within said casing and connected to said bolt, each of said members serving to effect a retraction of said bolt.

50. A lock including, in combination, a casing, a bolt, means for projecting said bolt beyond said casing, two pairs of operating members associated with said casing and each of the same serving to effect a retraction of said bolt, a key operated mechanism and a handle mechanism and means associated with both of said mechanisms whereby said different mechanisms may be optionally and operatively associated with either of said pairs of operating members.

55. A lock including, in combination, a casing, a bolt, means for projecting said bolt beyond said casing, two pairs of operating members associated with said casing and each of the same serving to effect a retraction of said bolt, a key operated mechanism and a handle mechanism, means associated with said mechanisms whereby said handle mechanism cooperates with one pair of said operating members and said key mechanism cooperates with one of the second pair of operating members and means for optionally prevent-

ing movement on the part of the other of said second pair of members and one of said first named pair of members.

16. A lock including a casing, a bolt, means for projecting the same beyond said casing, two pairs of operating elements, the elements of each pair being disposed in juxtaposition members operatively associated with said bolt and extending from each of said elements whereby, upon the latter being operated said bolt will be retracted, a key operated mechanism and a handle mechanism, means coupling said handle mechanism to either of said pairs and both of the operating elements thereof, means for coupling said key mechanism to either of said pairs and solely one of the operating elements thereof, and means for rendering inoperative one of the operating elements of either pair.

20 17. A lock including, in combination, a casing formed with an opening, a bolt extendable through said opening, said casing to be applied to a closure adjacent one of the edges thereof and with its opening extending 25 towards said edge, a key operated mechanism, a knob, said knob and mechanism occupying predetermined positions irrespective of whether the casing is disposed adjacent one or the other edge of said closure, and 30 similar means for interchangeably accommodating both said mechanism and knob according to the position of said casing with respect to said closure, and said means serving to connect both said mechanism and knob to said bolt whereby projection and retraction of the latter may be effected.

18. A lock including, in combination, a casing formed with an opening, a bolt extendable through said opening, said casing 40 to be applied to a closure adjacent one of the edges thereof and with its opening extending towards said edge, a key operated mechanism, a knob, said knob and mechanism occupying predetermined positions irrespective 45 of whether the casing is disposed adjacent one or the other edge of said closure, and similar means for interchangeably accommodating both said mechanism and knob according to the position of said casing with 50 respect to said closure, and said means serving to connect said mechanism and knob to said bolt whereby projection and retraction of the latter may be effected, and means for rendering said knob inoperative to effect a 55 retraction of said bolt.

In testimony whereof I affix my signature, in the presence of two witnesses.

JOHN HINES.
